UNITED STATES PATENT OFFICE.

JOHN WILLIAM BURBRIDGE, OF EATON, OHIO.

DESIGN FOR A TROLLEY-WHEEL.

SPECIFICATION forming part of Design No. 32,663, dated May 15, 1900.

Application filed April 18, 1900. Serial No. 13,398. Term of patent 14 years.

To all whom it may concern:

Be it known that I, JOHN WILLIAM BURBRIDGE, a citizen of the United States, residing at Eaton, in the county of Preble and State of Ohio, have invented a new and original Design for Trolley-Wheels, of which the following is a specification.

This invention relates to a new and original design for a trolley-wheel, and the essential feature resides in opposite circular heads with outer face concavities and an intermediate body with reversely-arranged angular grooves forming V-shaped tapering ridges.

The accompanying drawing illustrates a perspective view of a trolley-wheel embodying the features of the design.

The numeral 1 designates opposite heads of circular form having concavities 2 in the outer

faces, from the center of which are cylindrical tubular projections 3. Between the heads 1 ²⁰ is a body 4 of less diametrical extent and formed with a plurality of reversely-arranged angular grooves 5, separated by V-shaped tapering ridges 6, the latter beginning and merging without abruptness. ²⁵

Having thus described the invention, what is claimed as new is—

The design for a trolley-wheel, herein shown and described.

In testimony that I claim the foregoing as ³⁰ my own I have hereto affixed my signature in the presence of two witnesses.

JOHN WILLIAM BURBRIDGE.
